CLAIM

We claim the ornamental design for a handheld electronic device skin, as shown and described.

DESCRIPTION

FIG. 1 is a back perspective view of a handheld electronic device skin;

FIG. 2 is a back elevational view thereof;

FIG. 3 is a right elevational view thereof; and,

FIG. 4 is a left elevational view thereof.

The arrangement and juxtaposition of the component elements of the design relative to one another is part of the claimed design.

The broken lines shown in the drawings of the handheld electronic device skin are for the purpose of illustrating portions of the article that form no part of the claimed design.
